UNITED STATES PATENT OFFICE.

GEORGE RYAN BERRIEN, OF PRINCETON JUNCTION, NEW JERSEY.

MAIL-BAG DELIVERER AND CATCHER.

SPECIFICATION forming part of Letters Patent No. 698,358, dated April 22, 1902.

Application filed November 8, 1901. Serial No. 81,556. (No model.)

To all whom it may concern:

Be it known that I, GEORGE RYAN BERRIEN, a citizen of the United States, and a resident of Princeton Junction, in the county of Mercer and State of New Jersey, have invented a new and Improved Mail-Bag Deliverer and Catcher, of which the following is a full, clear, and exact description.

The invention relates to railway mail-service; and its object is to provide a new and improved mail-bag deliverer and catcher arranged to automatically deliver a mail bag or pouch from a car to a station and to pick up a mail bag or pouch at the station from the mail-car while the latter passes the station.

The invention consists of novel features and parts and combinations of the same, as will be fully described hereinafter and then pointed out in the claims.

20 A practical embodiment of the invention is represented in the accompanying drawings, forming a part of this specification, in which similar characters of reference indicate corresponding parts in all the views.

25 Figure 1 is a side elevation of the improvement, showing the mail-car in section and in position at a station to deliver a pouch and receive one. Fig. 2 is a plan view of the same, the car being shown in section. Fig. 3 is a sectional plan view of the same on the line 3 3 of Fig. 1. Fig. 4 is a sectional plan view of the mail-car arm and parts carried thereby. Fig. 5 is a transverse section of the same on the line 5 5 of Fig. 4. Fig. 6 is a perspective view of the pouch-support at the station. Fig. 7 is a perspective view of one of the pouch-holders, and Fig. 8 is a sectional side elevation of the lower part of the pouch-holder.

40 In the door-opening of a mail-car A is fulcrumed at B' an arm B, under the control of the person in charge of the mail-car to permit of swinging the arm into a horizontal position (see Figs. 1 and 2) whenever it is desired to deliver and receive a pouch at a station or to swing the arm into a vertical position when not in use and when past the station. On the outer end of the arm B is arranged a forwardly-projecting guide-bar B², on which 45 is mounted to slide a catcher C, adapted to engage a ring D, carrying a pouch-holder E, for holding a station-pouch F to be received

from the car at the station. The ring D is removably hung on a supporting-arm G, carried by a counterbalance-lever G', supported on a post or standard G², set on a suitable foundation adjacent to the track on which the mail-car travels in the direction of the arrow a'. The ring D also supports temporarily a pin H, extending at right angles from a slide H', 60 movable in an arm H², fulcrumed on a pivot-pin H³, carried by a collar H⁴, mounted to turn on a suitable bearing G³, arranged on the post or standard G². The slide H' is normally held in an innermost position (see Fig. 3) by 65 a spring H⁵, coiled on a rod H⁶, fulcrumed on the pivot-pin H³, and carrying at its free end a head H⁷, against which abuts one end of the spring H⁵, the other end of the latter pressing on the inner end of the slide H' to hold the latter in an innermost position, as shown in Fig. 3. On the rear end of the pin H is slidably held a catcher I, similar in construction to the catcher C and adapted to receive a ring D', carrying a pouch-holder E', similar to the 70 pouch-holder E, and serving to hold a mail-car pouch F' to be delivered at the station from the mail-car. The ring D' is hung on a supporting-arm J, attached to or forming part of the rear end B³ of the bar B², (see Fig. 5,) 75 the ring D' being also engaged at its bottom by an arm J', fulcrumed on the under side of the arm B. (See Figs. 1 and 5.) The arms J and J' are provided with spring-pressed pivoted retaining-catches J² and J³ to hold the 80 ring D' against accidental displacement, and a similar retaining-catch G⁴ is arranged on the top of the arm G to hold the ring D against 85 accidental displacement. (See Fig. 6.) On the arm B is arranged a fork J⁴ for engagement by 90 the inner side of the ring D' to hold the latter approximately parallel to the arm B to insure a proper passage of the ring D' into the catcher I, as hereinafter more fully explained. (See Fig. 2.) The catcher C, previously mentioned, is provided with a shank C', mounted to slide on the bar B² and having its forward end formed with a nose C², operating in conjunction with the free end of an entrance-catch C³, fulcrumed on the forward end of a 95 shank C⁴, arranged parallel with the shank C' and secured to a rear cross-bar C⁵, against which the ring D is adapted to abut. The catch C³ is pressed on by a spring C⁶ to nor-

mally hold the catch against the inside of the nose C² and to allow the catch to open inwardly upon engaging the ring D when the car passes the station in the direction of the 5 arrow a'. The catcher C is normally held in an outermost position on the bar B² by a spring C⁷, extending between the cross-bar C⁵ and the arm B, and the said spring C⁷ is coiled on a guide-rod C⁸, secured to the cross-bar C⁵ 10 and sliding in a bearing in the arm B. Thus when the holder E and the ring D enter the catch C³ the latter opens inwardly to permit the ring D and the holder E to pass upon the shank C' and to finally abut against the cross-bar C⁵, so that on the further forward movement of the car the holder is carried by the ring. The impact of the ring D on the cross-bar C⁵ causes the holder E to slide rearwardly 15 on the bar B² and against the tension of the spring C⁷, so that the ring and holder are not liable to be damaged, it being understood that as soon as the force of the impact is spent the spring C⁷ returns the holder E to a normal forward position on the bar B², as shown in 20 Fig. 4.

Each of the holders E and E' consists of an eye E², (see Fig. 7,) engaging the corresponding ring D or D', and on the eye are pivoted depending arms E³ and E⁴, between which is 25 passed the middle portion of the pouch or bag F or F'. The arm E³ is formed at its lower end with an inwardly-extending shank E⁵, having an arrow-head E⁶, adapted to be engaged by catches E⁷, pivoted on the lower end 30 of the arm E⁴ and pressed apart at their outer ends by a spring E⁸ (see Fig. 8) to hold the catches E⁷ normally in engagement with the arrow-head E⁶ and retain the pouch or bag in 35 position between the arms. When it is desired to place a pouch or bag in position in the holder E or E', the operator presses the outer ends of the catches E⁷ to disengage the latter from the arrow-head E⁶, and thereby allow of swinging the arms E³ and E⁴ apart 40 for placing the mail bag or pouch in position between the arms. The latter are now swung toward each other to reengage the arrow-head E⁶ with the spring-pressed catches E⁷ to lock the arms E³ and E⁴ in a closed position, and 45 with the mail bag or pouch securely held between the arms.

The catcher I consists, essentially, of a shank I', mounted to slide on the rear end of the pin H, (see Figs. 2 and 3,) the sliding motion of the shank being limited by a stop-pin I² on the shank, said stop-pin extending through an elongated slot H⁸ in the pin H. The rear end of the shank I' is provided with a nose I³, operating in conjunction with an 55 entrance-catch I⁴, fulcrumed on a shank I⁵, held on a cross-bar I⁶, integral with the forward end of the shank I'. A spring I⁷ holds the catch I⁴ normally in a closed position against the nose I³, and the catcher I is yieldingly 60 mounted on the rear end of the pin H, and for this purpose a spring I⁸ is interposed between the cross-bar I⁶ and the slide H', the

spring being coiled on a guide-rod I⁹, sliding in bearings in the slide H' and in the cross-bar I⁶.

The operation is as follows: The operator in charge of the station places the mail bag or pouch in position between the arms E³ and E⁴ of the holder E and then hangs the ring D onto the supporting-arm G to suspend the holder E and its pouch or bag F, as illustrated in Fig. 1, from the counterbalance-lever G'. The operator also swings the arm H², and with it the slide H', upward and turns the ring D sufficiently to allow of passing the pin H in engagement with the bottom of the ring adjacent to the eye E², as plainly indicated in Fig. 1. By this upward movement of the arm H² and slide H' the catcher I is moved into position for receiving the ring D' and its holder E' and pouch F'. The latter, contained in the mail-car, is placed by the attendant in charge thereof between the arms E³ and E⁴ of the holder E'. The ring D' of this holder is hung on the arms J and J', carried by the arm B, and when the car approaches the station the arm B is swung into a horizontal position, as shown in Fig. 1, so that the car in passing the station causes the catcher C to engage the ring D and move the same off the supporting-arm G and pin H, and at the same time the ring D' passes onto the catcher I and is disengaged from the arms J and J', so that the arm B is relieved of the ring D', the holder E', and pouch F', and supports the ring D, the holder E, and the pouch F. The arm B is now swung on its pivot B' by the attendant in charge of the mail-car, so that the ring D can be disengaged from the catcher C by swinging the catch C³ inward to move the ring out between the nose C² and catch C³. The catcher C is now opened and the pouch F is removed. As soon as the ring D is carried along by the catcher C on the forward movement of the car A the pin H is thus deprived of its support, and consequently the arm H², slide H', and parts carried thereby swing downward to carry the ring D', holder E', and pouch F' to the ground to allow the operator in charge of the station to remove the ring D' from the catcher I by swinging the catch I⁴ inward and passing the ring out between the catch I⁴ and nose I³. The holder E' is now opened and the pouch F' is removed and taken to the post-office.

From the foregoing it will be seen that no matter how fast the car is traveling the several devices readily function in a proper manner to cause the delivery of a mail-pouch from the car to the station and to insure the pouch from the station being picked up by the car without the slightest danger of the pouch being dropped or the parts of the device injured, as is so frequently the case with devices of the class now in use.

Having thus described my invention, I claim as new and desire to secure by Letters Patent—

1. In a device of the class described, the combination with a crane having means for suspending a mail-bag at a station, of an arm hung to swing toward and from the crane and provided with devices for engaging with said bag-suspension means, a car-bag catcher mounted and projecting from one side of the swing-arm and provided with a holding member and with a catch arranged to coöperate with said member.
2. In a device of the class described, the combination with a station-crane having bag-suspension devices, of an arm mounted to swing toward and from the crane, and having means adapted to engage with said station-bag-suspension devices, and a car-bag catcher yieldably mounted on said swing-arm and capable of a cushioned movement relative thereto under the impact of a car-bag, said catcher being movable with the swing-arm and having a holding member, and a catch arranged to coöperate with said member.
3. In a device of the class described, the combination with a station-crane, of a two-part swing-arm, one of the members of said arm being pivoted on the crane, and the other member being slidably fitted to the pivoted member, said slidable member being normally impelled by a spring, and having means adapted for engagement with a station-bag-suspension device.
4. A mail-bag deliverer and catcher, comprising an arm on the mail-car, a catcher yieldably mounted on the car-arm, a station mail-pouch support adapted to be engaged by said catcher on the car-arm and to be removed thereby from the station, a swinging station-arm held in an active position by said station mail-pouch support, a catcher yieldably held on said station-arm, and a car mail-pouch support carried by the car-arm and adapted to be delivered by the same to the second-named catcher which is carried by the swinging station-arm.
5. A device of the class described, provided with a mail-pouch support comprising a ring, an eye on the ring, arms pivoted on the eye, and a locking device for locking the free ends of the arms together, as set forth.
6. A device of the class described, provided with a mail-pouch support comprising a ring, an eye on the ring, arms pivoted on the eye, and a locking device for locking the free ends of the arms together, the said locking device consisting of a shank on the free end of one of the arms and having an arrow-head, and spring-pressed catches on the free end of the other arm and adapted to engage the said arrow-head, as set forth.
7. A device of the class described, provided with a station-post, a lever fulcrumed thereon, a ring removably hung on the said lever, a mail-pouch holder suspended on the said ring, an arm fulcrumed on the post, a spring-pressed slide movable in the said arm, and a pin on the said slide for engaging the said ring to hold the arm and slide in an operative position, as set forth.
8. A device of the class described, provided with a station-post, a lever fulcrumed thereon, a ring removably hung on the said lever, a mail-pouch holder suspended on the said ring, an arm fulcrumed on the post, a spring-pressed slide movable in the said arm, a pin on the said slide for engaging the said ring to hold the arm and slide in an operative position, and a catcher held in the said slide to receive the car mail-pouch carrier, as set forth.
9. A device of the class described, provided with a station-post, a lever fulcrumed thereon, a ring removably hung on the said lever, a mail-pouch holder suspended on the said ring, an arm fulcrumed on the post, a spring-pressed slide movable in the said arm, a pin on the said slide for engaging the said ring to hold the arm and slide in an operative position, and a catcher held in the said slide to receive the car mail-pouch carrier, the said catcher being yieldingly mounted on the said pin, as set forth.
10. A device of the class described, provided with a station-post, a lever fulcrumed thereon, a ring removably hung on the said lever, a mail-pouch holder suspended on the said ring, an arm fulcrumed on the post, a spring-pressed slide movable in the said arm, a pin on the said slide for engaging the said ring to hold the arm and slide in an operative position, and a catcher held in the said slide to receive the car mail-pouch carrier, the said catcher comprising a shank mounted to slide on the pin and having a nose, and a spring-pressed catch operating in conjunction with the said nose, as set forth.
11. A device of the class described, provided with a station-post, a lever fulcrumed thereon, a ring removably hung on the said lever, a mail-pouch holder suspended on the said ring, an arm fulcrumed on the post, a spring-pressed slide movable in the said arm, a pin on the said slide for engaging the said ring to hold the arm and slide in an operative position, a catcher held in the said slide to receive the car mail-pouch carrier, the said catcher comprising a shank mounted to slide on the pin and having a nose, a spring-pressed catch operating in conjunction with the said nose, and a cross-bar on the said shank, and carrying a second shank on which the spring-pressed catch is fulcrumed, as set forth.
12. A device of the class described, provided with a station-post, a lever fulcrumed thereon, a ring removably hung on the said lever, a mail-pouch holder suspended on the said ring, an arm fulcrumed on the post, a spring-pressed slide movable in the said arm, a pin on the said slide for engaging the said ring to hold the arm and slide in an operative position, a catcher held in the said slide to receive the car mail-pouch carrier, the said catcher comprising a shank mounted to slide

on the pin and having a nose, a spring-pressed catch operating in conjunction with the said nose, a cross-bar on the said shank, and carrying a second shank on which the spring-pressed catch is fulcrumed, and a spring interposed between the cross-bar and slide, as set forth.

13. In a device of the class described, the combination with a movable car-arm, of a 10 guide-arm projecting therefrom, and a station-bag catcher yieldably mounted on said guide-arm to give backwardly to the impact of a station mail-bag, said catcher having a holder member and a catch coöperating therewith.

14. A device of the class described, having a car-arm, a supporting-arm rigid thereon, a catch on the supporting-arm, a pivoted arm on the said car-arm, and a catch on the pivoted arm, as set forth.

15. In a device of the class described, the combination with a car-arm, of a guide-arm projecting therefrom, a station-bag catcher slidably mounted on said guide-arm, and 25 cushion operatively related to said catcher to absorb the shock due to the impact of a bag with the catcher.

16. In a device of the class described, a bag-catcher comprising a hollow holding member 30 provided with a nose at its extremity, a cross-bar solid with said member and provided

with a shank that lies adjacent to the member, and a yieldable catch mounted on the shank and spanning the space between the shank and the member to coöperate with the 35 nose thereof.

17. In a device of the class described, a bag-catcher having a holding member provided with a laterally-extending nose, a shank adjacent to said member, and a yieldable catch 40 spanning the space between the member and the shank, said catch being mounted on said shank to open inwardly from the nose and adapted to be seated firmly against said nose and to be limited in its closing movement 45 thereby.

18. In a device of the class described, the combination with a station-crane, and a swing-arm thereon, of a pin carried by said arm, a car-bag catcher slidably mounted on an end 50 portion of said pin and provided with a holding member and a catch, means for limiting the movement of the catcher, and a cushion device opposing the movement of the catcher.

In testimony whereof I have signed my 55 name to this specification in the presence of two subscribing witnesses.

GEORGE RYAN BERRIEN.
